(57) **CLAIM**

We claim the ornamental design for a lightbulb, as shown and described.

DESCRIPTION

FIG. 1 is an isometric view, from the top left, of the lightbulb,

FIG. 2 is an isometric view, from the bottom right, of the lightbulb.

FIG. 3 is a plan view from the bottom of the lightbulb.

FIG. 4 is a plan view from the top of the lightbulb.

FIG. 5 is an elevation view from the right side of the lightbulb.

FIG. 6 is an elevation view from the left side of the lightbulb.

FIG. 7 is an elevation view from the front of the lightbulb; and,

FIG. 8 is an elevation view from the back of the lightbulb.

Any broken lines are understood to be for illustrative purposes only and form no part of the claimed design.
